UNITED STATES PATENT OFFICE.

WILLIAM F. DIETZSCH, OF CHICAGO, ILLINOIS.

BREEZE COLLECTOR.

Application filed March 2, 1925. Serial No. 12,621.

This invention in general relates to devices for catching dust and more particularly to that type of devices termed breeze arresters or collectors for the dust, coke-breeze or débris delivered from and generated by water gas or carbureted water gas machines.

The ordinary type of machine for manufacturing water gases or carbureted water gas, is usually charged with material from a door in its upper or top portion. In producing gas with this type of machine a relatively high draft exists within the machine. Now, obviously, the moment the charging door is opened to replenish the materials within the gas making machine, a comparatively great blast is caused to be blown upwardly through the door in which blast is suspended small particles of carbon and other matter which are usually referred to as coke-breeze. A considerable quantity of gas is also drawn along with the blast as it escapes from the machine.

Now if this coke-breeze expelled from the gas machine is discharged directly into the atmosphere, it not only pollutes the air of the community, but it settles on the buildings and ground thereabout. Furthermore, by allowing the coke-breeze to be expelled into the atmosphere, it means that the machine is losing raw material or fuel and hence is unable to produce the maximum amount of gas for a given quantity of raw material. Also, the gas that makes its escape with the blast, is both poisonous and inflammable, and hence it should not be discharged into the room where the gas machine operators are located.

An object of the present invention is to provide an improved breeze collector or arrester of simple compact and inexpensive construction which may be quickly and easily applied to the usual gas manufacturing machine.

Another object of the invention is to provide an improved device of the above character in which the particles of coke and other material suspended in the blast are deflected from the blast before the bulk of the accompanying gas and air comprising the blast are permitted to make their escape into the atmosphere.

A further object of the invention is to provide a device of the above character in which the particles of carbon suspended in the blast are deflected completely into a suit-

able container for future consumption, thereby resulting in a substantial increase in efficiency of the gas manufacturing equipment.

A still further object of the present invention is to completely eliminate any danger of the gases discharged from gas making machines, making their entrance into the room where the operators are working.

I am aware that it is old to collect the particles of matter discharged with the blast in a gas machine, and to convey the gases into the atmosphere. The devices heretofore designed to accomplish these two features, have not proven very successful due to the fact that certain of the gases were permitted to make their escape before the particles of matter in suspension were deflected and hence a considerable amount of the suspended particles of matter accompanying the escaping gases into the atmosphere. In fact nearly all of the devices of this character heretofore have been successful in delivering the gases into the atmosphere, but as far as I am aware, none of them, although designed to accomplish this purpose, have been able to properly collect particles of matter carried out by the outrushing gases, due to the fact that considerable amounts thereof in being deflected were carried out by the escaping gases to the atmosphere. Then again, when the door of the gas machine was closed and the blast again enclosed, deflected particles of matter were free to fall back down the path over which they were forced by the onrushing blast, due to gravity, and hence were not collected in the container devised therefor. Moreover, the devices have heretofore been objectionable in that the particles of matter were deflected too many times before reaching the ultimate downward path over which they gravitate, and, hence, substantial quantities of this matter were lost on the rebound.

I propose in accordance with the features of the present invention to provide a device of simple construction preferably made of sheet metal and comprising a minimum number of bends or forms. In my device, after the particles of matter in suspension are once deflected, they are free on the rebound to gravitate over a suitable path into a container devised therefor. Also, the gases escaping with the blast are not permitted to enter the atmosphere until the particles of matter in suspension have been deflected and are free to gravitate. In other

words, at the time the gases are permitted to escape from the stack the particles are already on their downward path, falling due to gravity, and hence, inasmuch as this path is the one of least resistance, the particles will continue over this path into the container and will not be carried out by the outgoing gases.

Other objects and advantages of the present invention will more fully appear from the following detailed description, taken in connection with the accompanying drawings, which illustrate one embodiment thereof, and in which,

Fig. 1 is a side elevation of a gas machine to which is applied a breeze arrester or collector embodying the features of the present invention; and

Fig. 2 is a plan view of that portion of the arrester projecting through the roof.

I desire it understood that, although the features of the present invention are particularly applicable to gas machines, that they may be applied to many other types of industrial equipment and hence, are not to be limited in this particular use. However, I consider its application to gas machines as the preferred embodiment of my invention, and hence am illustrating and describing it in connection with gas machines.

Referring now to the drawings in detail, in which like reference numerals designate similar parts throughout the several views, 10 denotes a gas manufacturing machine which may be of any usual or suitable construction. The machine is positioned in a room, referred to generally hereinafter by reference numeral 11, provided with suitable beams 12, and a roof 13. Located in the room 11 adjacent machine 10, is a receptacle or container 14, into which the coke-breeze is delivered, as will be more fully described hereinafter. The coke-breeze in the container 14 may be withdrawn whenever desired through a discharge pipe 15, passing through the floor 16 into the room below (not shown).

The top portion 17 of the gas machine proper is provided with a door 18 through which material is admitted into the furnace for charging same. Positioned immediately over the door 18 is a funnel shaped or flared end 19 of a stack 20 passing through both the beams 12 and the roof 13. The end 19 of the stack 20 is supported and spaced from the top 17 of the gas machine 10 by suitable supporting elements 21. The other end of the stack 20 is provided with an elbow-like member or lateral bend 21 provided with a flared end or discharge orifice 22. This member 21 may, if desired, be detachably mounted to the stack 20. The bend provided for by the member 21 is slightly greater than that provided by a right angle elbow. Located

adjacent the flared end 22 of the member 21 is a tapered member 25 which gradually diminishes in size until its discharge orifice 24 is approximately the same as that of a downcomer pipe 25' to which it is suitably connected. The large end of the member 25 is spaced from but adjacent to the flared end 22 of the member 21 and is adapted to receive particles of matter discharged therefrom, or rather gravitated therefrom, as will be more fully described hereinafter.

The member 25 is provided and equipped with another outlet 26 which is connected by a small pipe 27 to the pipe 25' intermediate its ends. The pipe 25 is in communication with a vent pipe 29 through the means of a small section of piping 30 connected to the pipe 25' near its upper end and to the pipe 29 intermediate its ends. The vent pipe 29 is of usual construction and provides an escape outlet for the gases which might get into the member 25. The greater part of the gases will be permitted to escape through the means of the space separating the flared end 22 from the member 25. Both the pipes 29 and 25' terminate at their lower ends in the dust collector 14.

As previously mentioned, the parts constituting the breeze arrester may be made of sheet metal and suitable metal shapes. Due to the simplicity of design of my structure, it may be produced at a relatively small cost and may be applied very readily to the ordinary gas manufacturing machine. The only members in my construction of unusual or new design, are the members 21 and 25 which, although new, are of a simple construction. Suitably supported over the members 21 and 25 is a cover 35 for preventing rain from entering these members.

The operation of this mechanism is as follows:

Upon the door 18 being opened, the blast 110 arising from the furnace is of sufficient velocity to carry the coke-breeze particles along with it, as well as certain quantities of gas, as previously explained. These breeze particles are carried in a state of suspension in the blast, up through the stack 20, which is positioned to receive the entire effect of the blast. The blast upon reaching the upper part of the stack 20, strikes the upper portion 40 of the lateral bend or member 21, and rebounds, or rather is deflected out through the orifice provided for by the flared end 22 of the member 21. Obviously, upon the particles of coke or, namely, the breeze coke, coming in contact with the portion 40 of the member 21, they are deflected from their true course and lose practically all their initial velocity. After having rebounded from the portion 40, they gravitate down the member 21 and fall into

the member 25 by their own weight. The majority of the air and gas which accompanies the coke-breeze particles are free to escape from the member 21 into the surrounding atmosphere. The particles of matter in the member 25 gravitate along the incline thereof and are discharged through the opening 26 and the orifice 24 into the downgoing pipe 25'. The member 25 has just a sufficient amount of incline to permit the particles of matter discharged therein to gravitate along its inner surface to the two openings thereof.

Practically the entire amount of gases arising in the stack 20, as previously mentioned, are discharged between the space separating the members 21 and 25, but in order to provide an escape for any gases which might get into the pipe 25' and the receptacle 14, I provide a vent 29 which permits any such gases to escape into the atmosphere externally of the room 11.

It is evident that the construction of the member 21 is such that the particles of matter deflected thereby are free to rebound therefrom in a direction such that the angle of incidence is substantially equal to the angle of deflection. Furthermore, once the particles of matter rebound from the portion 40 of the member 21, they will be delivered into the member 25 practically without the need of any assistance of the accompanying gases, due to the fact that the end 22 of the member 21 is turned downwardly and hence the deflected particles of matter are free to gravitate in the member 25 rather than be forced there by the initial velocity of the accompanying gases. Then, too, the blast upon reaching the lateral bend 21 tends to follow the upper part of the bend, whereas, the particles of matter tend to drop to the bottom of the bend and are free to thereafter gravitate into the receptacle 25. The cover 35 is supported over the members 21 and 25 in such a manner as to completely cover the space separating the ends of the two members from the downpour of rain, snow and sleet. Obviously, the ends of the two members may be completely enclosed by a cover provided with suitable openings for the escape of gas without departing from the present invention. In fact, this may be desirable where the natural elements such as wind are unusually turbulent and powerful, so as to prevent any of the particles of matter discharged in the member 25 from being blown into the atmosphere. But as a general rule, the ordinary wind will only tend to augment the downward flow of the matter discharged in the member 25, blowing same completely down the pipe 25' into its receptacle 14.

It is to be understood, that although the preferred embodiment of the present invention is disclosed herein, that the inven-

tion is not to be limited therby, but only in so far as defined by the scope and sphere of the appended claims.

I claim:

1. In combination, a stack through which a blast in which particles of matter are suspended may travel, an elbow-like member on an end of said stack having a discharge orifice pointing downwardly, the said particles of matter being adapted to rebound from the said elbow-like member and to be deflected downwardly through the said discharge orifice of the member, a second member positioned externally of the stack and spaced from said elbow-like member adapted to receive the particles of matter discharged therefrom, the space intermediate the said two members serving to permit the accompanying gases to make their escape, and a container connected to said second member for receiving the particles of matter so discharged.

2. In combination, a stack through which a blast in which particles of matter are suspended may travel, an elbow-like member on an end of the said stack having a discharge orifice pointing downwardly, the said particles of matter adapted to rebound only once in the said elbow-like member and to then be deflected downwardly through the said discharge orifice of the member, a second member positioned externally of the stack and spaced from said elbow-like member into which the particles of matter may gravitate from the elbow-like member, the space intermediate the said two members permitting accompanying gases to make their escape, a container adapted to receive the particles of matter due to gravity, and a connection between the second member and the container.

3. In combination, a stack through which a blast in which particles of matter are suspended may travel, a lateral bend on an end of the said stack adapted to separate the gas comprising the blast from the particles of matter, an adjacent receptacle, the said particles being partly deflected and partly gravitated into the adjacent receptacle, the said receptacle being positioned externally of the stack and being spaced from the end of the said lateral bend to permit the gases to make their escape, the said receptacle having a downward incline so as to permit the particles of matter discharged therein to gravitate, a pipe connected to the said receptacle down which the particles of matter may gravitate, and a container at the end of the pipe for receiving the particles of matter.

4. In combination, a stack through which a blast in which particles of matter are suspended may travel, a lateral bend on an end of the said stack having a discharge orifice pointing downwardly, a receptacle spaced

4

from the end of said lateral bend terminating in a discharge orifice, a pipe connected to said discharge orifice, the said lateral bend causing the particles of matter to be separated from the said blast, the said particles of matter being partly deflected by the lateral bend and partly gravitating into the said receptacle, the said blast tending to follow the uppermost portion of the said lateral bend and to escape through the space separating the receptacle from the lateral bend, the particles of matter in the said receptacle being adapted to gravitate through the orifice thereof into the said pipe, a container associated with the other end of the said pipe into which the particles of matter may be discharged, and a vent pipe connected to both the first pipe and the container for permitting any gas which may accompany the particles of matter into the receptacle to make its escape.

5. In combination, a stack having a flared end adapted to entrain a gas in which particles of matter are in suspension, a lateral bend on the upper end of the stack having a flared discharge orifice pointing downwardly, the said bend causing the gas to segregate into the upper portion of the bend and the particles of matter into the lower portion of the bend, a receptacle spaced from the flared end of the lateral bend inclined downwardly, said particles of matter being adapted to be deflected by the bend into the receptacle, partly due to the rebound of the said particles and partly due to gravity, the gas constituting a blast making its escape into the atmosphere through the space separating the flared end of the lateral bend from the receptacle, a container for storing the particles of matter, and means connected to the inclined receptacle for causing the particles of matter therein to gravitate into the said container.

6. In combination, a stack provided with a flared end adapted to entrain a gas having particles of matter in suspension therein, the other end of the said stack having a lateral bend provided with a flared discharge orifice, a receptacle adjacent the said flared end of the lateral bend and spaced there-

from, the said receptacle being inclined downwardly and gradually diminishing in size to terminate in a relatively small discharge orifice, a pipe connected to the said relatively small discharge orifice at one end, a container connected to the other end of the said pipe, a connection between the said receptacle and the pipe intermediate its end, a vent connected to the container and the pipe, and a cover disposed and supported over the said flared end of the lateral bend and the uppermost portion of the receptacle to prevent the natural elements from entering or affecting the contents of the said receptacle.

7. In combination, a stack through which a gas in which particles of matter are suspended may travel, a lateral bend formed on the end of the said stack having a discharge orifice pointing downwardly, the said particles of matter being adapted to rebound from the said lateral bend and to be deflected downwardly through the discharge orifice of the bend, and a member positioned externally of the stack and spaced from the said lateral bend adapted to receive the particles of matter discharged therefrom, said space intermediate the bend and member serving to permit the accompanying gas to make its escape.

8. In combination, a stack through which a gas in which particles of matter are suspended may travel, the end of the said stack being formed so as to have a discharge orifice pointing downwardly, said particles of matter being adapted to rebound from the said formed end of the stack to be deflected downwardly through the said discharge orifice, and a member positioned externally of and independent of the said stack spaced from the said formed end adapted to receive the particles of matter discharged therefrom, the said space intermediate the formed end and the member serving to permit the accompanying gas to make its escape.

In witness whereof, I hereunto subscribe my name this 27th day of February, 1925.

WILLIAM F. DIETZSCH.
